DESIGN FOR A CHAIR

Einar Anderson, New York, N. Y.

Application November 12, 1941, Serial No. 104,113

Term of patent 7 years

To all whom it may concern:

Be it known that I, Einar Anderson, a citizen of Sweden and resident of New York city, in the county of New York and State of New York, have invented a new, original, and ornamental Design for a Chair, of which the following is a specification, reference being had to the accompanying drawing, forming a part thereof.

In the drawing:

Fig. 1 is a side elevational view of a chair, showing my new design.

Fig. 2 is a perspective view of the same.

I claim:

The ornamental design for a chair, as shown.

EINAR ANDERSON.
